TELEPHONE APPLIANCE

Filed June 12, 1928

FIG. 1

FIG. 2

FIG. 3

EDWARD McCANN

INVENTOR

BY

J. Waters
ATTORNEY

UNITED STATES PATENT OFFICE

EDWARD McCANN, OF NEW YORK, N. Y.

TELEPHONE APPLIANCE

Application filed June 12, 1923. Serial No. 284,731.

This invention relates to an appliance for use with telephones of the kind comprising a device capable of being fitted over the usual telephone mouthpiece and serving to enable 5 a conversation to be carried on in comparative privacy. The invention consists in an improvement in appliances of this kind and has for its main purpose to provide an appliance capable of being readily attached to 10 and disconnected from a telephone mouthpiece so that it may be quickly attached when it is desired to conduct a conversation without being heard by other persons even when positioned close to the speaker.

15 A further object of the invention is to enable such a conversation to be carried on in low or normal speaking tones and to be clearly audible by the other party to the conversation.

20 A still further object of this invention is to provide an appliance of the kind referred to which shall be more sanitary than those heretofore known.

The special features and advantages of my 25 invention will appear more particularly from the following description and the appended claims.

In the drawings:

Figure 1 is a side elevation partly in section on the line 1—1 of Fig. 2;

Figure 2 is a front elevation and;

Figure 3 is a rear elevation.

The appliance comprises a casing preferably of metal designated by the numeral 1, 30 this casing in the form illustrated being of cylindrical form and having its rear end 2 of a reduced cross-section. Fitting within said rear end 2 of the casing and preferably extending somewhat beyond it as illustrated 35 in Figure 1 is a lining or gasket 3 of rubber or the like provided with an inwardly turned flange 4 seated against the end of an inwardly extending portion or flange 5 of the rear end 2 of the casing. This rubber lining or gasket 3 fits over the telephone mouthpiece and serves not only to exclude sound by insuring a close fit but by its resilience enables the appliance to be fitted to mouthpieces of slightly varying size.

40 Extending transversely of the casing and

clamped between said flange 4 and the end of a lining member 6 of rubber or equivalent material is a reticulated membrane or diaphragm 7 which as illustrated is in the form of a wire mesh fabric preferably of fine 55 copper-nickelized net which serves to circulate the air and which has an important effect in increasing the volume of normal tones and greatly improving the clarity of the speaking voice.

At its front or outer end the casing 1 is provided with an annular disk 8 forming a cover, the inner portion of which is bent inwardly and extended to form a tubular sound conduit 9 which as illustrated terminates 65 short of the membrane 7. A lining or gasket 10 fits snugly around the conduit 9. The mouthpiece 11 of the device of any suitable material such as vulcanite is sufficiently large to permit the lips of the user to be 70 inserted therein without inconvenience and it is preferably elliptical with outwardly extending points as shown in Figures 1 and 2. A tubular stem 12 of the mouthpiece 11 fits frictionally in the conduit 9 and may 75 readily be removed when desired for cleaning for instance.

The annular disk 8 is provided with holes 13 which add to the sanitary character of the device and to the comfort of the user 80 by permitting the foul air to escape and furthermore by permitting circulation of air assist in improving the volume and clarity of the voice.

If desired the vulcanite of which the 85 mouthpiece is composed may have incorporated with it one or more ingredients, such as phenol which are permanently antiseptic.

By the use of my device it is impossible for a conversation to be overheard even at 90 a short distance and a conversation can be conducted in privacy while the device enables a low or normal voice clearly to be heard at the other end of the line even in long distance connections. It is not necessary in 95 using my device to press the mouth tight into the mouthpiece it being sufficient to hold the lips lightly against the mouthpiece.

What I claim and desire to protect by Letters Patent is:—

1. A device of the character described comprising a casing one end of which is adapted to be fitted over a telephone mouthpiece, a tubular sound conduit extending partly through the interior of said casing, a mouthpiece fitting into said conduit, and a reticulated membrane or diaphragm extending transversely of said casing.

5 2. A device of the character described comprising a casing having a reduced end portion adapted to be fitted over a telephone mouthpiece, a resilient lining member in said reduced portion, a tubular sound conduit extending partly through the interior of said 10 casing, a mouthpiece fitting into said sound conduit, and a reticulated membrane or diaphragm extending transversely of said casing.

15 3. A device of the character described comprising a casing, a resilient liner fitting within the rear end of said casing, a resilient liner fitting within the front end of said casing, a reticulated membrane extending transversely of the casing and clamped between 20 said two liners, a tubular sound conduit extending into said casing, and a mouthpiece having a stem frictionally fitting within said sound conduit.

25 4. A device of the character described comprising a casing, a resilient liner fitting within the rear end of said casing, a resilient liner fitting within the front end of said casing, a reticulated membrane extending transversely of the casing and clamped between 30 said two liners, a tubular sound conduit extending into said casing but terminating short of said membrane, a mouthpiece having a stem fitting within said sound conduit, and means for permitting escape of foul air 35 from said casing.

40 5. A device of the character described comprising a casing, a resilient liner fitting within the rear end of said casing, a resilient liner fitting within the front end of said casing, a reticulated membrane extending transversely of the casing and clamped between 45 said two liners, a tubular sound conduit extending into said casing but terminating short of said membrane a mouthpiece having 50 a stem fitting within said sound conduit, a resilient gasket snugly fitting around said sound conduit and means for permitting escape of foul air from said casing.

55 6. A device of the character described comprising a casing, a resilient liner fitting within the rear end of said casing, a resilient liner fitting within the front end of said casing, a reticulated membrane extending transversely of the casing and clamped between 60 said two liners, a tubular sound conduit extending into said casing, and an approximately elliptical mouthpiece having a stem frictionally fitting within said sound conduit.

65 7. A device of the character described com-

prising a casing, a wire mesh diaphragm extending across the interior of said casing, a resilient liner within the rear or inner end of the casing, a perforated annular disk forming a cover for the front or outer end of the 70 casing, said disk being extended inwardly to form a tubular sound conduit and a mouthpiece having a stem fitting within said sound conduit.

75 8. A device of the character described comprising a casing, a wire mesh diaphragm extending across the interior of said casing, a resilient liner within the rear or inner end of the casing and projecting beyond the end thereof, a perforated annular disk forming 80 a cover for the front or outer end of the casing, said disk being extended inwardly to form a tubular sound conduit and an approximately elliptical mouthpiece having a stem fitting within said sound conduit.

85 9. A device of the character described comprising a casing, a wire mesh diaphragm extending across the interior of said casing, a resilient liner within the rear or inner end of the casing and projecting beyond the 90 end thereof, a perforated annular disk forming a cover for the front or outer end of the casing, said disk being extended inwardly to form a tubular sound conduit and an approximately elliptical permanently anti-septicized mouthpiece having a stem fitting within said sound conduit.
